UNITED STATES PATENT OFFICE.

GUSTAV EMANUEL ERICKSON, OF NEW YORK, N. Y.

AUTOMATIC ELECTRIC WATER-PURIFIER.

1,199,253.

Specification of Letters Patent. Patented Sept. 26, 1916.

Application filed December 28, 1915. Serial No. 69,111.

To all whom it may concern:

Be it known that I, GUSTAV EMANUEL ERICKSON, a subject of the King of Sweden, and a resident of 451 Ninth street, in the 5 borough of Brooklyn, city of New York, county of Kings, and State of New York, have invented certain new and useful Improvements in Automatic Electric Water-Purifiers, of which the following is a specification.

The purpose of this invention is to provide an electric water sterilizer and filter which will purify water flowing at full pressure.

One advantage of this invention is to provide an apparatus of this class which is very compact and at the same time highly efficient.

Another advantage is to provide an apparatus of this class which can be readily taken apart for inspection.

Another advantage is to provide in conjunction with an apparatus of this class a signal to show that current is flowing when 25 the water has been turned on.

Another advantage is to provide in conjunction with an apparatus of this class a filter directly secured to the face of the apparatus.

Another advantage is to provide in conjunction with an apparatus of this class a switch directly secured to the rear face of the apparatus, operated by the valve handle which controls the water supply.

Another advantage is to provide an apparatus of this class which is entirely sanitary, and attractive in appearance.

Another advantage is to provide an apparatus of this class wherein the possibility 40 of shocking the operator has been eliminated.

Another advantage is to provide an apparatus of this class which is mainly supported by the inlet pipe.

Further advantages and possibilities will 45 become apparent as the specification proceeds.

In the drawings, Figure 1 is a front view of an apparatus embodying this invention. Fig. 2 is a side view of the same. Fig. 3 is 50 a front view of the casing 2 of Fig. 2, with

cover 3 removed, disclosing plate 35. Fig. 4 is a view of the vertical cross section of Fig. 1 through the center. Fig. 5 is a rear view of Fig. 3 disclosing the switch box 13 and mechanism within. Fig. 6 is a view of 55 the active side of plate 34 of Fig. 4.

It is a well established fact that water when properly exposed to action of an electric current will lose all of its microbe and bacterial content by decomposition and have 60 its impurities rendered flocculent or curdled, making the removal of these impurities then comparatively easy by filtering. Experience has shown that aluminum electrodes are among the most practical for the 65 purpose, and hence the employment of such in the form of grooved plates, 34 and 35, either cast or struck from sheets of the metal.

It has been found convenient to have the 70 filter 5 cast in one piece with the cover 3. The main body or casing 2 of the apparatus is made of any dielectric substance suitable for the purpose, such as porcelain, glass, hard rubber or insulating composition. Porcelain is preferred, owing to its sanitary 75 appearance and condition as well as economy in price.

A switch box 13 is attached to the rear of casing 2, thereby adding directly to the 80 utility of the apparatus and utilizing space that would otherwise be waste.

A signal in the form of a light 1 has been found useful in signaling the presence of electric current in the apparatus when water 85 is flowing through the same, and in calling attention when the water has been left flowing.

Referring to the drawings, the operation and construction of the apparatus are as 90 follows:

Water arrives from the mains in pipes 48 of Fig. 4 where it may be tapped from faucet 46 in its ordinary state. It will otherwise flow up through the T elbow 47 and 95 pipe 20 into chamber 44 in valve 19 when the cylinder 43 is turned clockwise by pushing back the handle 8 shown in Figs. 1 and 2. The water continues upward through pipe 22 and in through aperture 23 in cas- 100

ing 2 and thence up between the convolutions of aluminum plates 34 and 35. Plate 35 is secured in place by two screws 30 and 38.

5 Screw 30 is capped with a flat contact in the switch box 13, shown also in Fig. 5. Plate 34 rests with flange 2' in Fig. 5 upon the depressed shoulder 2' of casing in Fig. 3, all shown in cross section in Fig. 4, where 10 the superposed disk of fiber 26' is disclosed as resting in the same depression for the purpose of insulating plate 34 from the exterior metallic cover 3.

In Fig. 5 the aperture 31' in plate 34 is 15 the same as that which accommodates contact 31 in Fig. 4, this contact being capped with a flat contact nut in the switchbox 13, shown also in Fig. 6.

When handle 8 of Figs. 1 and 2 is pushed 20 as stated extension 21 draws down vertical link 9 and the horizontal arm 12 connected thereto by bolt 11, arm 12 descending vertically in slot 10, then Figs. 4 and 6, portions 49 and 53 of plate 12, 49 and 53 move 25 down in guides 50 and 54, and the contact head on the extreme right of rod 52 passes the lump on contact plate 40, and by virtue of the spring mounted on rod 52 exerts a pressure sufficient to swing dielectric switch 30 bar 42 anticlockwise about center bolt 29 to connect by means of metallic forks 41 and 51 contacts 31 with 32, and 30 with 39, Bar 32 connects with charged wire 15, and bar 39 connects with another wire 15, both 35 wires passing upward through collar 14 and being connected to a plug 16 of Fig. 1.

Returning to Figs. 4 and 6, the water from inlet 23 passes upward between the grooved plates 34 and 35, the ridges 28 of 40 plate 34 as shown in Fig. 5 extending when in position as shown in Fig. 3 partly into grooves 24 of plate 35 and vice versa. Between the plates the water is now traversed by the electric current which curdles the 45 suspended and dissolved impurities to practical completion by the time the water reaches aperture 33. Thence, it continues through fiber disk 26' and cover 3 into chamber 4' of hood 4, whence it descends 50 through the cotton stuffed in chamber 5' of the filter 5. Seeping through the cotton, the water loses all suspended content and proceeds down through perforated filter plate 45 in bottom cap 17, and out through 55 spout 18.

The cover 3 is preferably cast in one piece with hood 4 and filter 5, and is secured to the porcelain body 2 by means of wing nuts on bolts 7, 7', being four in number, as 60 shown in Figs. 1 and 2, the holes in body 2 for the same being shown in Fig. 3 where one hole is noted 7'. The bolts 7, 7' in Fig. 1, and 7' in Fig. 2 are shown in a rear view

in Fig. 6, where 7' is shown as being electrically connected to inlet pipe 22 by strip 65 36, forming a ground between the inlet and the outlet or filter. This removes the possibility of a shock being received when operating the apparatus.

In order to insure a waterproof joint between the edge of casing 2 and the edge of cover 3, a groove 6' as also shown in Fig. 3 is occupied by a rubber gasket 6, a corresponding groove existing in the cover 3.

In Figs. 4 and 6 are shown bolt 38 which 75 interiorly secures plate 35 in position and connects the same with exterior strip 37, the latter extending down into socket 1' and connecting with light 1. In Fig. 6 is shown the hole 26 wherein is located the bolt 80 26 of Fig. 4, the inner hooked end contacting with the flange of plate 34, the point of contact on the flange being noted as 26 in Fig. 5. The outer end of bolt 26 connects with strip 8', the latter contacting with the 85 side of socket 1' and thus with light 1. This results in having the light connected to the plates and parallel with them, but entirely dependent upon them for source of current. Thus, if the current for any reason 90 should fail to reach plates 34 and 35 when the valve 19 is opened by handle 8, the light would also fail to register a signal, showing instantly that something was wrong and needed immediate attention. 95

Having thus fully described my invention, what I desire to claim as new, and to secure by Letters Patent is:

1. An electrolytic water purifier comprising a shallow receptacle having a substantially plane portion attached to a bounding wall with a shoulder or step upon the inner edge, a flat electrode or plate secured to the inner surface of said plane portion by means of a screw or contact communicating through said plane portion with exterior electric circuit, a second electrode or plate located in said receptacle with its periphery occupying said shoulder and with a screw or contact securing the same in position and connecting it with exterior electric circuit through said first plate without contact therewith and through said plane portion, substantially as described.

2. In an electrolytic water purifier containing electrodes or plates, a casing comprising an annular receptacle having the edge or bounding wall of uniform height, an extension upon one side of said wall having an aperture in the same containing an electric light socket with conductors passing from the socket through the rear of said aperture, an electric switch being housed and secured upon the rear of said receptacle, said conductors connecting with said switch, and below said switch an inlet aperture ly-

ing within said bounding wall and passing through the rear of the receptacle, and a plurality of flues passing through said receptacle in the bounding wall, providing 5 bolt channels whereby bolts may retain a cover upon said receptacle, substantially as described.

3. In an apparatus as described, a bolt or screw communicating with one pole of 10 an electric switch and with a metallic plate by means of contact of the sides of a head or fork on said bolt with the edge of an aperture in said plate, a casing inclosing said plate, a space between said plate and 15 the inner rear surface of said casing, a second metallic plate within said casing secured to said inner surface by means of a screw communicating with a second pole of 20 said switch through said surface, said bolt also running through said surface and the first plate, said first plate having a clearance aperture all about said bolt, and said casing having a raised portion in the form 25 of a hub about said bolt in said plate aperture, and means for manually operating said switch, substantially as described.

4. An apparatus as described, including 30 plates within a casing, the casing being in a vertical position, a cover and an electric light, said light being located above said 35 cover in a socket embedded in the material of said casing, a switch mounted on the said casing and conductors from said plates to said switch through said casing, means for 40 connecting said plates with said socket and light, said means comprising on one hand a screw bolt securing one of said plates to the inner rear surface of said casing and 45 communicating with a conductor on the rear surface of the same casing, said conductor connecting with said socket through an orifice in said rear surface; on the other hand, a bolt connecting by contact of the end thereof with a flange or extension of the 50 other of said plates and running through said casing from a shoulder within the edge thereof to the rear surface of the same and there connecting with a conductor running on said rear surface to said orifice and there 55 connecting with said socket, substantially as described.

5. An apparatus as described, comprising 60 a casing, a metallic cover, an inner plate and an outer plate spaced apart within said casing, a disk of insulating material interposed between said outer plate and said cover, an inlet in said cover and corresponding apertures in said insulating disk and outer plate, an inlet in said casing and corresponding clearance aperture or cutaway portion providing a space between said inner plate and inlet, bolts through said casing securing said cover to said casing, one

of said bolts connecting at the rear with 65 said inlet by means of a conductor at the rear of said casing, said cover, bolt and conductor constituting an electric ground between said inlet and outlet, substantially as described.

6. In an electrolytic water purifier including 70 a normally vertical casing, a cover comprising a normally vertical detachable plate with a filter upon a portion of one side of the same, forming an integral part thereof and constituting a projection from 75 said plate, an outlet in said plate said filter extending beyond and below the edge of the plate, and having an opening normally capped with a detachable cap containing a 80 spout, substantially as described.

7. An electrolytic water purifier comprising 85 an electric switch, a casing and a plate constituting a cover removably bolted to the casing, a flexible gasket compressed between the edge of said casing and said plate, an 90 inlet in the rear surface of said casing and said switch being directly mounted upon said rear surface and above said inlet, the latter being provided with an inlet pipe having a valve, an outlet in upper portion 95 of said plate within the periphery thereof, and a filter secured to said plate and being connected to said outlet, said filter occupying a portion of said plate and overhanging the edge at the bottom of the same, said 100 filter having a lower opening outside the apparatus and a spouted cap fitted to said opening, substantially as described.

8. An electrolytic water purifier, including 105 a switch comprising a reciprocal sliding member working in a pair of guides, an arm extending from one end of said member constituting a means whereby said member may reciprocate, an extension to either side on said member between said 110 guides and a post on each said extension and a slidable rod passing through said posts transversely to said reciprocal member, a spring on said rod pressing the same against a plate located on the side of a 115 dielectric bar at the central portion thereof, said plate having a rise from either end toward the center, said bar being reciprocably mounted on a center or pivot and capped at either end with contact fingers so as to be capable of simultaneously connecting two poles with each end of said pivoted bar, substantially as described.

9. An electrolytic water purifier including 120 a reciprocating snap switch with a switch arm, a casing, a manually operated valve upon said casing having a valve spindle with a rigid arm extending from one end of the same at an angle thereto, and a handle extending from the other end, a vertical link pivotally connected to the ex-

tremity of said valve arm extending up to said switch and directly connecting with the switch arm of same, providing positive parallel action of said snap switch with said valve being exclusively a manually operated device.

Signed at New York, in the county of
